UNITED STATES PATENT OFFICE

99,345

DESIGN FOR AN ADJUSTABLE TABLE

Glenn B. Culbertson, Dayton, Ohio

Application February 10, 1936, Serial No. 61,069

Term of patent 7 years

To all whom it may concern:

Be it known that I, Glenn B. Culbertson, a citizen of the United States, residing in the city of Dayton, in the county of Montgomery and State of Ohio, have invented a new, original, and ornamental Design for an Adjustable Table, of which the following is a specification, reference being had to the accompanying drawing, forming a part hereof.

The figure is a perespective view of an adjustable table, showing my new design.

I claim:

The ornamental design for an adjustable table, as shown.

GLENN B. CULBERTSON.
